[57] ABSTRACT

A stable insecticidal mixture comprising (1) phthalimidomethyl mono thio- or dithio-phosphates or phosphonates having the structural formula

wherein X is oxygen or sulfur, R is alkyl having 1 to 4 carbon atoms and R¹ is alkyl having 1 to 4 carbon atoms or alkoxy having 1 to 4 carbons (2) water and (3) phosphoric acid.

2 Claims, No Drawings

STABILIZED AQUEOUS SUSPENSION OF
PHTHALIMIDOMETHYL MONO THIO-OR
DITHIO- PHOSPHATES OR PHOSPHONATES

This invention relates to a stabilized aqueous suspension of certain phthalimidomethyl mono thio- or dithio- phosphates or phosphonates with phosphoric acid.

The certain phthalimidomethyl mono thio- or dithio- phosphates or phosphonates are those having the structural formula

where X is oxygen or sulfur, preferably sulfur; R is alkyl having 1 to 4 carbon atoms, preferably methyl and R¹ is alkyl having 1 to 4 carbon atoms or alkoxy having 1 to 4 carbon atoms, preferably methoxy. These compounds are known insecticides and evidenced by U.S. Pat. No. 2,767,194 and others.

The most preferred compound is N-(mercaptomethyl)phthalimide-S-(O,O-dimethylphosphorodithioate) having the structure

These compounds are stable when formulated with organic solvents however they decompose when formulated as aqueous suspensions in hard water (water having a pH above 8.0). The exact method mechanism of the decomposition is not fully understood; however, it is theorized that hydrolysis of the compounds occur when they are exposed to such water.

Generally the decomposition causes no serious limitations in the use of the compounds as insecticides. However, in applications where aqueous suspensions of the compounds are stored for long periods of time, several weeks, deleterious decomposition of the compounds has been observed. An example of such applications would be dipping of cattle in large vats to control various insects and ticks. In such dipping operations it is desirable to use or store the dip vats over long periods of time such as several weeks or months.

Quite unexpectedly it has been found that phosphoric acid greatly retards the rate of decomposition of the recited compounds when they are used in aqueous solutions or suspensions.

Although it is known in the art that aqueous solutions of the above recited compounds are rendered more resistant to hydrolysis by lowering the pH of the solution, the unexpected and superior results obtained from the use of phosphoric acid can not be explained.

The phosphoric acid can be added to the recited compounds either by using phosphoric acid or by forming it in situ from such compounds as super phosphate.

Even the smallest amount of phosphoric acid is useful. However, it is preferred to utilize about 0.01 to 0.5 percent by weight of water, and more preferably 0.01

to 0.05 percent by weight of water to stabilize the compounds for long storage.

Stabilization is best achieved by uniformly dispersing the phosphoric acid throughout the solution or suspension of the recited compounds.

The stabilization of aqueous suspensions of the phthalimidomethyl mono thio- or dithio- phosphates or phosphonates with phosphoric acid is illustrated in the following example.

EXAMPLE I

The following formulation is used in a test to determine the effectiveness of N-(mercaptomethyl)phthalimide-S-(O,O-dimethylphosphorodithioate) against house flies before and after treatment with phosphoric acid.

	Parts by weight
1.	N-(mercaptomethyl)phthalimide-S-(O,O-dimethylphosphorodithioate)
2.	Kaolin clay
3.	Sodium alkyl naphthalene sulfonate
4.	Sodium lignosulfonate
5.	Hydrated silica

The above formulation is prepared in a 5 liter suspension at 0.05 percent active ingredient. A reference vat is prepared and the pH is adjusted to 8.5 from 7.5 using 130 milliliters sodium hydroxide to simulate hard water.

A second identical vat is prepared using 130 milliliters (0.1N) phosphoric acid.

Each vat was bioassayed at 0, 4 hours, 1, 5 and 9 days, after preparation to determine any decomposition of the active ingredient. The results are recited in Table I.

TABLE I

Time	LD ₅₀ Values - $\mu\text{g}/25 \text{ H.F.}^*$	
	Phosphoric Acid Vat	Hard Water Vat
0 hours	1.8	2.3
4 hours	2.3	> 5.0
1 day	1.9	>100
5 days	2.5	—
9 days	1.8	—

* Values of 2.0 to 2.5 are normal and acceptable insecticidal values for the active ingredient of the formulation.

As can be seen from the test results the vat that contained the phosphoric acid remained constant for 9 days whereas the vat that simulated hard water lost a significant portion of its activity after only 4 hours.

We claim:

1. A stable insecticidal composition comprising an insecticidally effective amount of a compound of the formula

wherein X is oxygen or sulfur, R is alkyl having 1 to 4 carbon atoms and R¹ is alkyl having 1 to 4 carbon

atoms or alkoxy having 1 to 4 carbon atoms, water and phosphoric acid in an amount of 0.01 to 0.5 percent by weight of water.

2. The composition of claim 1 wherein X is sulfur, R is methyl and R¹ is methoxy.
